UNITED STATES PATENT OFFICE.

JOHN W. JOHNSON, OF LEAVENWORTH, KANSAS.

BIT-HOLDER.

1,060,845.

Specification of Letters Patent.

Patented May 6, 1913.

Application filed July 5, 1912. Serial No. 707,742.

To all whom it may concern:

Be it known that I, JOHN W. JOHNSON, a citizen of the United States, and a resident of Leavenworth, in the county of Leavenworth and State of Kansas, have invented a new and Improved Bit-Holder, of which the following is a full, clear, and exact description.

The object of the invention is to provide a new and improved bit holder or brace chuck arranged to facilitate the exchange of different bits, to securely hold bits of different sizes securely in position and to prevent pulling of the bit out of the socket while the bit is in use. For the purpose mentioned use is made of a head having a split socket for the reception of a bit shank, a sleeve mounted to turn on the said head and adapted to close the members, the socket on turning the sleeve also having lengthwise movement on the said head, and wedging jaws adapted to wedge between the socket members and the bit shank and moving lengthwise with the said sleeve.

A practical embodiment of the invention is represented in the accompanying drawings forming a part of this specification, in which similar characters of reference indicate corresponding parts in all the views.

Figure 1 is a sectional side elevation of the bit holder with the jaws and socket members in open position; Fig. 2 is a similar view of the same with a bit inserted and the socket members and jaws in closed or locking position; Fig. 3 is a side elevation of the head, the socket and the jaws in open position and the sleeve shown in section; Fig. 4 is a transverse section of the bit holder with the parts in position as shown in Fig. 2; Fig. 5 is a sectional plan view of the same on the line 5-5 of Fig. 3; Fig. 6 is a similar view of the same on the line 6-6 of Fig. 1; and Fig. 7 is a perspective view of the wedging jaws and with the spring arms open.

The head A of the bit holder or brace chuck is provided with a split socket at its forward end to provide spring socket members B, B having tapering V-shaped recesses B' at their inner opposite faces for the reception of the square tapering end C of the bit to be held in place in the holder or chuck. The forward ends of the socket members B, B are somewhat reduced and are provided with exterior cam surfaces B² adapted to engage corresponding cam surfaces D' integral on the inner surface at the forward end of

the sleeve D, mounted to turn and to slide lengthwise on the head A. Thus when the sleeve D is turned the cam surfaces D' acting on the cam surfaces B² cause the socket members B, B to move inward toward each other, thus securely clamping the shank C of the bit in place in the socket, and when the sleeve D is turned in the opposite direction, the socket members B, B are released and turn by their own resiliency into normally outward or open position.

The V-shaped tapering recesses B' of the socket members B, B terminate at their outer ends in outwardly-inclined V-shaped guideways B³ engaged by correspondingly-shaped wedging jaws E, E provided at their inner edges with bevels E' adapted to engage the shank C at the forward end thereof with a view to hold the bit against being pulled out of the socket during the time the bit is in use. The jaws E, E are held on spring arms F extending rearwardly between the socket members B, B, and the rear ends of the spring arms F are provided with lugs F' slidably engaging a guideway A' formed on the head A in the rear of the split, as will be readily understood by reference to the drawings. The forward ends of the wedging jaws E are in close proximity to an annular shoulder D² extending inwardly on the forward end of the sleeve D, and the lugs F' are in close proximity to an annular shoulder D³ extending inwardly in the rear end of the sleeve D, so that when the latter is moved lengthwise on the head A the jaws E move with the sleeve, and when the sleeve D is moved rearwardly from the position shown in Figs. 1 and 3 to the position shown in Figs. 2 and 4, then the jaws E are caused to travel inwardly toward each other owing to the tapering guideways B³ in which the jaws E are mounted to slide. When the sleeve D is moved outwardly from the position shown in Figs. 2 and 4 to the position shown in Figs. 1 and 3 then the jaws E move into open position owing to the action of the spring arms F with a view to release the shank of the bit.

In using the device the sleeve D is moved into outward position limited by the lugs F' reaching the forward end of the guideway A' to allow of inserting the shank C into the socket formed by the socket members B, and when this has been done the operator slides the sleeve D rearwardly on the head A to cause the jaws E to move rear-

wardly and to wedge between the socket members B and the forward end of the shank C, as plainly indicated in Fig. 2. The operator then turns the sleeve D on the head A to cause the cam surfaces D' to act on the cam surfaces B', as previously described, with a view to move the socket members B inwardly toward each other thus firmly gripping the shank C between them.

- 10 From the foregoing, it will be seen that by the arrangement described the shank C of the bit is not only firmly gripped between the socket members B but is also engaged by the wedging jaws E to securely hold the bit from being pulled out of the socket. When it is desired to remove the bit from the holder, the operator turns the sleeve D to cause the cam surfaces D' to release the socket members B, and then the sleeve D is moved forward and with it the clamping wedges E to move the latter out of engagement with the shank C of the bit, and the latter can now be withdrawn.

It will be noticed that if the square tapering end of the shank C is short, it is necessary to slide the sleeve D farther back on the head A than when the said end is longer, but in either case the tapering wedges E are firmly wedged in place to hold the bit

30 against being pulled out of its socket.

Having thus described my invention, I claim as new and desire to secure by Letters Patent:

1. A bit holder, comprising a split socket 35 for the reception of a bit shank, means for clamping the socket on the bit shank, and jaws at the outer end of the socket, forming inward projections and adapted to be wedged between the socket and bit shank to 40 prevent the bit from being pulled out of the said socket.

2. A bit holder, comprising a head having a split socket for the reception of the bit shank, a sleeve mounted to turn on the 45 said head and adapted to close the members of the socket on turning the sleeve, and jaws adapted to wedge between the socket member and the bit shank and moving lengthwise with the said sleeve.

3. A bit holder, comprising a head having a split socket for the reception of the bit shank and provided with tapering guideways, spring-supported jaws adapted to engage the said guideways, and a sleeve 55 mounted to turn on the said head and to slide lengthwise thereon, the said sleeve having means engaging the said jaws and moving the same lengthwise and the sleeve having means engaging the said split socket to 60 tighten the same on the bit shank or to release the same on turning the sleeve.

4. A bit holder, comprising a head having a socket split lengthwise to form spring members for receiving a bit shank between them, the forward ends of the said socket members being provided at the inner faces with outwardly tapering guideways and the said socket members having their forward ends provided exteriorly with cam faces, a sleeve mounted to turn and to slide on the 65 said head and provided at its ends with interior annular shoulders, the said sleeve being provided adjacent the forward shoulder with cam faces adapted to engage the cam faces on the said socket members to close 70 the same, and wedging jaws engaging the said socket guideways and having their rear ends provided with tapering clamping edges adapted to engage the bit shank, the said jaws being provided with rearwardly-extending 75 spring arms terminating in transversely-extending lugs abutting against the inner shoulder of the said sleeve, the forward ends of the jaws abutting against the forward shoulder of the sleeve to cause the 80 jaws to move lengthwise.

5. A bit holder comprising a head having a socket split lengthwise to form spring members for receiving a bit shank between them, the forward ends of the said socket members being provided at the inner faces with outwardly-tapering guideways, and the said socket members having their forward ends provided exteriorly with cam faces, a sleeve mounted to turn and to slide on the 90 said head and provided at its ends with interior annular shoulders, the said sleeve being provided adjacent the forward shoulder with cam faces adapted to engage the cam faces on the said socket members to close 95 the same, wedging jaws engaging the said socket guideways and having their rear ends provided with tapering clamping edges adapted to engage the bit shank, the said jaws being provided with rearwardly-extending spring 100 arms terminating in transversely-extending lugs abutting against the inner shoulder of the said sleeve, the forward ends of the jaws abutting against the forward shoulder of the sleeve to cause the jaws to move lengthwise with the sleeve, and rear guideways on the said head engaged by the said lugs of the spring arms limiting the forward and backward sliding movement of the said 105 sleeve and the wedging jaws.

In testimony whereof I have signed my name to this specification in the presence of two subscribing witnesses.

JOHN W. JOHNSON.
